UNITED STATES PATENT OFFICE

JOHAN VIKTOR BLOMQUIST, OF STOCKHOLM, SWEDEN, AND MARCEL EHLINGER, OF MULHOUSE, FRANCE, ASSIGNEES TO AKTIEBOLAGET ATMOS, OF STOCKHOLM, SWEDEN, A CORPORATION OF SWEDEN

ROTATING STEAM BOILER

Application filed March 19, 1931, Serial No. 523,820, and in France July 7, 1930.

The present invention refers to improvements in connection with rotating steam boilers of the type comprising a central container communicating with a plurality of tubes mounted around the former in a squirrel-cage like formation, and wherein separate tubes are provided for admission of feed water to the steam generating tubes and for delivery of the generated steam therefrom. Thereby the central container may also contribute to the steam generation, and may serve as a receiver for the steam generated within the tubes. During the rotation of the boiler, a part of the feed water entering the steam generating tubes is returned to the central container, and the construction of the communication means between the steam generating tubes and the container is of such a kind that said tubes cannot be entirely emptied.

A special difficulty in connection with rotating steam boilers of this type is caused by the impurities entering together with the feed water, as it has not hitherto been possible effectively to prevent or to remove the collections of sludge arising within the steam generating tubes. It has been found that the collection of sludge and the deposit of incrustations have especially arisen at the ends of the steam generating tubes remote from the admission pipes for the feed water.

The invention has for its main object to eliminate the difficulty referred to in the foregoing by establishing a continuous flow of the feed water in the same direction throughout the entire length of the tubes. This is performed by introduction of the feed water into the tubes at one end of the tubes only, the other end of the same being connected with the partly water-filled central container, so that substantially no collection of sludge can occur in the steam generating tubes as the sludge together with the amount of water returned from the tubes to the central container is conveyed to the latter, from which the sludge may be blown off either continuously or intermittently at suitable intervals.

The efficiency of the invention may be further increased by the arrangement of scraper chains within the steam generating tubes such chains effectively preventing the sludge from

adhering to the interior walls of the tubes.

Another means adapted for still further improvement of the result is the provision of an injector for increasing the rapidity of water flow through the steam generating tubes, this injector acting under influence from the fresh feed water forcibly fed in and serving to convey an additional amount of water from the central container in circulation through the steam generating tubes together with the fresh feed water.

In the following the invention is to be described by reference to the accompanying drawing showing an embodiment thereof, the single figure in the drawing representing a longitudinal section of the boiler body. For the sake of convenience it is suitable to describe the invention by reference to its manner of action.

The fresh feed water is introduced by means of the hollow pivot 1 mounted in a suitable stuffing box (not shown), and from the said hollow pivot the water, by means of the tubes 2, is conveyed to one end of the steam generating tubes 3, which are positioned around the central container 4 in a squirrel-cage like formation previously known. At their opposite ends the tubes 3 are connected with the central container 4 by means of return pipes 5, such pipes extending within the tubes 3 substantially to the centre of the same so as to form an overflow for preventing the tubes from being entirely emptied during the rotation of the boiler.

At the operation of the boiler, the water is displaced from the left to the right in the drawing by means of the tubes 3, a part of the same being converted into the form of steam when passing the tubes 3, the remainder flowing further through the return pipes 5 into the central container 4. The tubes 3 are interiorly provided with scraper chains 3^a which at the rotation will continually perform a scraping action against the inner face of the generating tubes so as to prevent any deposit of impurities on the tube walls, the impurities contained in the water being then conveyed by the flow of the same into the central container.

In order to prevent a deposition of the impurities on the inner face of the container 4, such container is also provided with a scraper chain 4^a.

5 The generated steam is delivered through a fixedly mounted pipe 6 provided with an upwardly bent inner end positioned at a level above the surface of the bulk of water within the container 4.

10 A draining pipe 7 having a down-bent inner end is also provided within the container 4 such pipe extending into the bottom portion of the container, and by means of the same a certain amount of water may be continually or periodically blown off from the container, then conveying the impurities therefrom and keeping the interior water content in a clean state.

15 By means of the arrangements stated in the foregoing the invention involves a steam generator, which may be used for the generation of steam of very high pressures when fed with non-distilled or non-purified water, and in which the disadvantages caused by 20 incrustations are entirely eliminated.

25 It has also been found to be possible to accelerate the flow of water through the generator, and especially through its generating tubes, by means for instance of an injector, which consists of a tube 8 mounted coaxially around the steam delivery tube 6 and acts for the sucking in of additional feed water to the generating tubes 3 from the central container 4, such additional feed 30 water forming a circulation feed water flow.

35 This injector means may for instance consist of a reduced or throttled portion 9 of the tubular feed water inlet pivot 1, in which the outlet end of the pipe 8 is mounted. By 40 the increased rapidity of flow of the fresh feed water when passing the throttled entrance portion 9, the water from the central container will be sucked in by means of the pipe 8 and added to the amount of fresh feed 45 water introduced to the pipes 3.

From the foregoing it will thus be apparent that the rapidity, or amount of water per unit of time, of the flow of circulation through the tubes 3 and the central container 50 4 may be materially increased, and thereby the said tubes are effectively washed clean.

55 At intervals it may be desired entirely to empty the tubes 3, and for this purpose the pipes 5 are provided with a little bore 10 positioned adjacent to the inner generatrix of the tubes, i. e. the portion of the same nearest to the axis of rotation. When it is desired entirely to empty the tubes 3, the steam boiler is rotated at a very slow speed, so that all 60 of the water contents within those tubes 3 taking a position above the water level within the container 4 have a sufficient time to flow back into the said container through the said bores 10.

65 It will easily be understood that it is ad-

vantageous to mount the steam generating tubes in a manner so as to permit the same a free expansion independently of each other when acted upon by the heat. At their one end the tubes 3 are rigidly connected with the return pipes 5 having a substantial diameter, and for the aforesaid purpose the feed pipes 2 must therefore be shaped in a manner permitting an easy deformation. In the embodiment shown in the drawing, this may be arrived at by constructing the feed pipes 2 in the form of coils permitting the variation in length of the steam generating tubes 3, for instance as shown in the drawing.

70 The steam boiler body according to the invention may be mounted so as to rotate around a horizontal axis, or even the axis of rotation may take an inclining position.

75 What we claim and desire to secure by Letters Patent is:—

1. In a rotating steam boiler of the character described, a central container, a plurality of steam generating tubes positioned in a squirrel-cage like formation around the same, means for the force-feed admission of 80 fresh feed water at one end of the said steam generating tubes independently of the central container, means for connecting the opposite ends of the said tubes with the said container, and means for delivery of the 85 generated steam from the latter.

90 2. In a rotating steam boiler of the character described, a central container, a plurality of steam generating tubes positioned in a squirrel-cage like formation around the same, means for the force-feed admission of 95 fresh feed water at one end of said steam generating tubes independently of the central container, means for connecting the opposite ends of the said tubes with said container, a scraper means mounted in each of the 100 said steam generating tubes, and means for delivery of the generated steam from the central container.

105 3. In a rotating steam boiler of the character described, a central container, a plurality of steam generating tubes positioned in a squirrel-cage like formation around the same, means for the force-feed admission of 110 fresh feed water at one end of the said steam generating tubes, means for returning of additional feed water from the central container to the generating tubes at the same 115 end of the latter, means for connecting the opposite ends of the said tubes with the central container, and means for delivery of the generated steam from said container.

120 4. In a rotating steam boiler according to claim 3, the additional feature of a scraper means mounted in each of the steam generating tubes and connected with the opposite ends of the same.

125 5. In a rotating steam boiler of the character described, a central container, a plurality of steam generating tubes positioned in a 130

- 5 squirrel-cage like formation around the same, means for the force-feed admission of fresh feed water at one end of the said steam generating tubes independently of the central container, injector means actuated by the fresh feed water forcibly fed in and adapted for returning of additional feed water from the central container to the generating tubes at the same end of the latter, means for connecting the opposite ends of the said tubes with the central container, and means for delivery of the generated steam from said container.
- 10 6. In a rotating steam boiler according to claim 5, the additional features of a scraper means in each of the steam generating tubes and in the central container, and means for blowing off the sludge from the bottom portion of the latter.
- 15 7. In a rotating steam boiler of the character described, a central container, a plurality of steam generating tubes positioned in a squirrel-cage like formation around the same, an inlet for fresh feed water to the tubes, a flexible pipe connection connecting each of the steam generating tubes at one end of the boiler with said feed water inlet independently of the central container, rigid tubular return pipe connections between the generating tubes and the central container at the opposite end of the boiler, and means for delivery of the generated steam from the said container.
- 20 8. In a rotating steam boiler according to claim 7, the additional features that the rigid return pipe connections are extended into the steam generating tubes so as to form over-flow outlets therefrom, and that small sized outlet means are provided in the extended return pipe ends in a position adjacent to the portion of the steam generating tubes nearest to the axis of rotation.
- 25 9. In a rotating steam boiler according to claim 7, the additional features of scraper means in each of the steam generating tubes and in the central container, and means for blowing off the sludge from the bottom portion of the latter.
- 30 10. In a rotating steam boiler of the character described, a central container, a plurality of steam generating tubes positioned in a squirrel-cage like formation around the same, an inlet adapted for the force-feed admission of fresh feed water to the tubes, a flexible pipe connection connecting each of the steam generating tubes at one end of the boiler with said feed water inlet independently of the central container, rigid tubular return pipe connections between the generating tubes and the central container at the opposite end of the boiler, such return pipes being adapted to form over-flow means within the steam generating tubes, injector means actuated by the fresh feed water forcibly fed in and adapted for returning an additional

amount of feed water from the central container to the generating tubes at the inlet end of the latter, and means for delivery of the generated steam from the said container.

11. In a rotating steam boiler according to claim 10, the additional feature that the over-flow means formed by the return pipes are provided with by-pass means of a comparatively small capacity.

12. In a rotating steam boiler according to claim 10, the additional features of scraper means in each of the steam generating tubes and in the central container, and means for blowing off the sludge from the bottom portion of the latter.

In testimony whereof we have signed our names to this specification.
